UNITED STATES PATENT OFFICE

ARTHUR J. MANKIN, OF PHILADELPHIA, PENNSYLVANIA, ASSIGNOR TO TRIUMPH HOSIERY MILLS, INC., OF NEW YORK, N. Y., A CORPORATION OF NEW YORK.

KNITTING MACHINE.

Application filed April 16, 1925. Serial No. 23,421.

The invention relates to knitting machines and relates more particularly to the rotary or circular type of knitting machines such as is exemplified in spring needle machines 5 of the Wildman type.

The invention contemplates as its general object to provide means adapted to be used in connection with a knitting machine of the character described, for automatically forming 10 a reinforcing splice on the work while it is being knitted, of vari-colored thread if desired, and more particularly for forming a high splice of stepped configuration and pleasing design on ladies' hose, which high 15 splice is of short width at its top portion where it is commenced and gradually increases in width as the knitting progresses downwardly, the stepped formation obtaining its greatest width at its lowermost 20 portion.

The invention is of particular utility in knitting a stocking where it is desirable and customary to form the splice at the heel of the stocking to properly reinforce the 25 fabric as well as to provide a completed stocking having a vari-colored splice of pleasing design. This reinforcing splice when formed above the heel is commonly called the high splice and in most instances 30 has been formed rectangular in shape. The additional yarn for forming the splice is brought into and out of its feeding position, relative to the knitting needles, by means of a finger, commonly called the high splicing finger. This finger is raised and lowered 35 relative to the needles by means of a cam having a high and lower portion formed on its surface so that when the point of the stocking is reached for forming the high 40 splice, the finger is brought under the control of the cam to thus feed additional yarn or thread to certain of the needles and thereby to form the rectangular splice.

In other types of high splicing mechanism 45 it has been the practice to knit a high splice having non-parallel sides and of substantially triangular configuration. This has been effected by varying the length of the low portion of the cam which operates the 50 high splicing finger as the knitting progresses, resulting in the yarn feeding periods of the splicing finger being of gradually increasing duration with the result that the number of needles supplied with the reinforcing yarn are increased or decreased to

form the high splice having non-parallel sides. This has been effected in certain instances by means of two circumferential movable members carried by the cam and adapted to vary the length of the low portion 60 of the cam as the knitting progresses.

A further object of the invention is to provide high splicing mechanism of the character described which is designed to be used in conjunction with the spring needle 65 knitting machines of the Wildman type and which is automatically actuated at the proper point to knit a superposed high splice of pleasing and novel design and of vari-colored thread if desired, without affecting 70 or interfering with the usual operating mechanism and needles engaged in knitting the main or body portion of the stocking. To this end the invention is adapted to be readily attached to a spring needle knitting 75 machine of the character described and which may be readily detached when desired, after which removal the knitting machine may be used independently of the high splicing mechanism without readjustment. By 80 the invention the attachment may be used on Wildman spring needle knitting machines without changing the position or relation of the usual high splicing finger with respect to the usual main yarn fingers or needle cylinder. 85

In knitting without the attachment constituting the invention, stockings are completed in the usual manner and the high 90 splicing finger drops in to knit a rectangular reinforcing splice half way around the stocking and in conjunction with the needles forming the lower leg and foot portion, the high splicing finger dropping in as soon as the heel is reached and thereby knitting a 95 double thickness in the stocking at this point. The high splicing finger is prevented at this time from knitting the other half of the stocking, by the usual cams provided for the purpose on such machines, and which pull the needles down as they pass the high splicer finger to prevent the needles from catching the high splicer thread; the usual main yarn needles remaining in operation and taking thread from the particular main yarn finger which is in operation; to knit a single thickness and complete the remaining half circle of stocking.

By the attachment constituting the present invention, the high splicing finger is 110

caused to drop in at a point higher up in the stocking. Instead of knitting a reinforcing splice to form a double heel thickness half way around the stocking as above described, the arrangement of needle controlling cams obtained by the invention, causes a high splice of stepped formation of a reinforcing character and pleasing design, to be knitted above the heel until the point is reached where the high splicing finger is ordinarily dropped in; and, at this point the knitting proceeds as described above to complete the stocking, and in exactly the same manner as if the attachment were not present. It will be therefore apparent that the provision of the attachment constituting the present invention, provides a high splice of stepped configuration superposed above the usual heel splice of substantially rectangular shape, and this desirable improvement is effected without changing the usual operative relation of the high splice finger relative to the main yarn fingers or to the needle cylinder or head.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:

Fig. 1 is a perspective view of a portion of a Wildman spring needle knitting machine and showing the ring attachment and certain of the operating parts constituting the present invention, in position thereon. The knitting machine illustrated is of usual and known construction and has therefore been largely diagrammatically delineated, only such operating mechanism being shown as is necessary to a complete understanding of the present improvements for knitting the stepped high splice design above the heel of the stocking. This knitting machine is illustrated as embodying a rotating needle cylinder or head having a stationary cam ring for operating the vertical needles in the needle cylinder, but it is not desired to limit the invention to such a machine, as it is possible to use the same in connection with a machine having a stationary needle cylinder and a rotating cam ring.

Fig. 2 is a perspective view similar to

Fig. 1 but looking from the opposite side of the machine, the mechanism for operating the main yarn guide being omitted for convenience in illustration. This mechanism for operating the main yarn guide is shown in Fig. 1 and is of standard construction and forms no part of the present invention.

Fig. 3 is a side elevation of the machine and showing certain cams operating in conjunction with the ring attachment, and which cams are located on the far side of the machine as viewed in Fig. 1.

Fig. 4 is an enlarged side elevation of the ring attachment constituting the present invention and illustrating its manner of connection to the rotating cylinder dial of the knitting machine.

Fig. 5 is a plan view of the ring attachment member illustrated in Fig. 4, and showing the projecting lugs with their attachments as designed for knitting machines of the described class.

Fig. 6 is an enlarged vertical sectional view on line 6—6 of Fig. 5.

Fig. 7 is a similar view on line 6—6 of Fig. 5, showing only the ring member proper.

Fig. 8 is a perspective view of one of the sliding guide members having the projecting lugs and which are illustrated in Figs. 5 and 6.

Fig. 9 is a detail perspective view of the spring member illustrated in Fig. 6.

Fig. 10 is a detail perspective view of the block member illustrated in Figs. 2 and 3 and showing the manner of attachment of the various cams thereto which operate in conjunction with the rotating ring member and its attached parts.

Fig. 11 is a detail elevational view showing the high splice design effected by the invention, and which is worked just above the heel at the back of the stocking.

Fig. 12 is an elevational view of a stocking adapted to be knitted in the spring needle machine, illustrated in the drawings, and showing at its lower portion the location and nature of the high splice design effected by the present improvements.

Fig. 13 is an enlarged detail horizontal section through a portion of the needle cylinder or head, and showing in plan view the arrangement and action of the various stationary and movable cams.

Fig. 14 is an enlarged side elevation of the needle cylinder and showing the action of stationary cam 57 on the long needle butts 58.

Fig. 15 is a similar view showing the action of movable cam 59 on the short needle butts 62.

Fig. 16 is a similar view showing the ring member 40 and the action of the movable cam 74 on the lugs 53 to 53° of the block members carried by said ring member.

Fig. 17 is a view similar to Fig. 16 but diagrammatic in character as though all of the lugs 53 to 53^a were arranged in the same plane, and showing the elevating action of stationary cam 56 on said lugs after the latter have been moved downwardly by movable cam 74.

Fig. 18 is a diagrammatic view showing the selective and progressive portion of the high splice needles, controlled by the lugs 53 to 53^a, to knit the various steps of the design.

Referring to the drawings, the knitting machine in conjunction with which the attachment is designed to be used comprises the usual standards 1 and top portion 2. The knitting cylinder or head is indicated at 3 and is adapted to be rotated from the power source of the machine in the usual manner. The rotating needle head 3 carrying the vertical needles 3^a is designed to contact and cooperate with the usual stationary cam (not shown) by means of which the needles are periodically raised and lowered to catch and clear the thread or yarn and perform the knitting operation in accordance with the usual known practice in machines of this character. Referring to Fig. 1, the main yarn guides or fingers are shown at the left hand of the machine and this mechanism is of usual or preferred construction in machines of this type. It will be sufficient to state that the main yarn fingers 4, 5, 6, 7 and 8 are raised or lowered by the cams 9, 10, 11, 12 and 13 through the medium of interposed cooperating levers indicated at 14, when it is desired to place the yarn fingers out or in knitting position. The main yarn or thread strands are indicated at 15 and are fed from suitable spools or reels (not shown) to the outer ends of the yarn fingers 4 to 8. It will be understood that when the yarn fingers are raised the needles 3^a are unable to catch the yarn while the needles are rotating.

The high splicer finger is indicated at 16 and is designed to be raised or lowered by the cam 17 through the action of lever 18 when it is desired to place the splicing yarn out or in knitting position. The high splice thread or yarn 19 which may be of varicolored silk if desired, is conducted from the usual reel (not shown) through an upright tubular guide post 20 and to the end of the high splicer finger 16 where it is engaged or cleared by the needles according to whether the high splicer finger is in or out of knitting position as determined by the cam 17 and lever 18.

The main yarn finger cams 9, 10, 11, 12, 13 and the high splicer finger cam 17 are caused to rotate by means of a ratchet 21 and pawl 22, acting by power through rocking movement of the lever 23 loosely mounted on the transverse shaft 24 and rocked by power ap-

plied through the movement of the lever 25. The latter is automatically and periodically reciprocated from the usual power source of the machine (not shown) to move the yarns carried by the main yarn fingers 4 to 8 and high splicer finger 16 into and out of position to be engaged and caught by the rotating needles 3^a of the needle cylinder 3, and as determined by the progress of the work.

Referring to Fig. 12, it will be seen that at the start of knitting the stocking, yarn or thread from finger 5 is in; this means that finger 5 is in the down position by the action of cam 10 (Fig. 1), and the yarn is being knit into the stocking. Yarn fingers 4, 6, 7, 8 and high splicer finger 16 are out of knitting position and are held up by the action of the cams 9, 11, 12, 13 and 17 (Fig. 1).

With further reference to Fig. 12, it will be seen that after the knitting has progressed to the point 26, finger 5 is thrown out of action by its cam and finger 6 is thrown in, and the knitting progresses by the action of this finger feeding yarn to the rotating needles 3^a until the point 27 has been reached. At this point the high splicer finger 16 is lowered into operating position by its controlling cam, yarn finger 6 remaining in. This results in a double thickness being knitted for the full circumference of the stocking down to the point 28. Here the high splicer finger 16 is thrown out and yarn finger 6 remains in to complete a single thickness of knitting as far as the point 29. Yarn finger 6 is thrown out by its cam and finger 8 comes in, which knits the tubular lower leg portion of the stocking down to the point 30 where the mechanism forming the subject of the present invention is automatically brought into play to knit the high splice stepped design in the manner indicated by the reference characters 31, 32, 33, 34 and 35.

Were the machine to be operated independently of the attachment contemplated by the present invention, there would be no change in operation at the point 30 and needles fed by yarn finger 8 would continue to receive yarn and knit the stocking down to the point 36 (Fig. 12). The usual rectangular splice formed by these machines would be ordinarily commenced at the point 36 and is caused by the high splicer finger 16 being thrown in by its cam to knit the rectangular splice for substantially one-half way round the stocking. It will be understood that yarn guide or finger 8 is in knitting at the same time so that eight or more needles are knitting into the stocking the yarn from high splicer finger 16, thereby making a double knit step. The high splicer finger 16 being in knitting position from the point 36 and yarn guide 8 being in, there is a high double heel knit half way round the stock-

ing. To prevent yarn from high splicer 16 from being knit into the remaining half of the stocking, the usual cams of the machine (not shown) pull down the needles as they pass high splicer finger 16, and yarn finger 8 continues to knit a single thickness to complete the half circle of stocking.

Still assuming that the present improvements are not attached to the machine, the knitting proceeds to the point 37 where finger or guide 8 is thrown out, high splicer finger 16 is also thrown out, and yarn finger 4 comes in, to knit the lower foot portion of the stocking. The usual cam action is brought into play to knit the proper configuration of the heel between the point 37 and the point 38, and at this latter location 4 is out, 8 again comes in and high splicer finger 16 comes in, which together knit the bottom of the stocking to the point 39. At this location yarn finger 8 goes out; high splicer finger 16 goes out, and yarn finger 4 comes in to complete the toe of the stocking.

The foregoing operations are standard with machines of this class and the improved mechanism for effecting the stepped design indicated at 31 to 35, and which may be of vari-colored thread, will be described. With further reference to Fig. 12, by means of the automatic improved cam actuated attachment constituting the invention, the high splicer finger 16 is thrown into operation at the point 30 instead of at the point 36, with a result that as additional needles are brought into play through the operation of my improved attachment, a high splice design of stepped configuration and pleasing appearance and which may be of vari-colored thread, is effected above the usual splice portion of substantially rectangular formation, and which latter, according to known methods, is commenced at 36 to be continued downwardly. By the invention, the high splicing finger 16 is dropped down and yarn is knit into the stocking by as many needles as are permitted to be put in knitting position. The number of needles in up or knitting position and catching yarn or thread from the high splicing finger 16, is governed by the improved mechanism constituting the present improvements. As the stepped high splicing operation is being performed, the needles that are not knitting in the yarn from the splicing finger 16, are being automatically pulled down by the operation of the attachment, and at every revolution of the needles. The latter are again forced to high knitting position by the usual cams (not shown) on all knitting machines, so that yarn from yarn finger 8 will knit the complete circular leg. The number of needles that are being forced up in knitting position by the attachment to catch yarn from

the high splicing finger 16, govern the width of each step in the design.

Following the design steps to the point 35 (Fig. 12), the stepping operation is completed, and thereafter the knitting proceeds 70 as in any knitting machine. The high splicer finger 16 being in knitting position and yarn finger 8 also being in, there is a high double heel knitted half-way around the stocking. The yarn from the high splicer finger is prevented from being knitted into the other half of the stocking by the usual cams which pull the needles down as they pass the high splicer finger as above described.

From the foregoing description and explanation it will be observed that according to the present invention the high splicer finger 16 is not changed in its position or relation to the five other yarn fingers 4, 5, 6, 7 and 8 with the exception that the high splicer finger is dropped in at the point 30 for the first step instead of dropping in at the point 36, as is the case in knitting without the mechanical attachment constituting the invention.

The attachment effecting the above described improvements consists in a ring member or element 40 which is preferably of metal and composed of two sections having ears 41 which enable the ring to removably embrace the needle cylinder 3. The sections are secured together by means of screws or bolts 42 and the assembled ring is adapted to be removably secured by means of the apertured lugs or ears 43 to the rotating cylinder dial 44 of the knitting machine (Figs. 4 and 5). The cylinder dial carries the rotating needle cylinder 3 and it will be apparent that the ring 40 rotating with the cylinder, bears always the same relation to the various needles and their respective butt jacks as the same revolve with the cylinder.

As best shown in Figs. 5 to 9, one of the ring sections is provided with a plurality of spaced grooves 45 which are designed to carry and loosely guide for vertical reciprocation a corresponding number of block members 46 having centrally and vertically disposed projections 47 thereon adapted to engage the guiding grooves 45 of the ring. The lower ends of these blocks 46 are designed to contact with and control the butt jacks of certain of the needles reciprocating within the ring in a manner to be herein-after described. The ring 40 is apertured opposite each of the block members as at 48 to house a plurality of latching balls 49, and a corresponding number of springs 50 are secured as by screws 51 to the outer surface of the ring and bear at their lower ends against the balls to yieldably press the latter into engagement with suitably disposed grooves 52 in the projections 47 of the blocks

46. The lower ends of the blocks are provided with outwardly projecting lugs, which as best seen in Fig. 5, are of varying lengths. The blocks 46 are equally spaced on each side of the vertical center of the ring as viewed in Fig. 5, and the innermost pair of blocks, one on each side of the center, are provided with the shortest outwardly projecting lugs 53. Thence the succeeding 10 pairs of lugs increase successively in length as at 53^a, 53^b, 53^c, 53^d and 53^e, the outermost lugs 53^e being of greatest length. The radial distance or spacing between each pair of lugs as viewed in Fig. 5 is preferably 15 approximately one-sixteenth of an inch. It will be apparent from an inspection of Fig. 6 that the several blocks 46 are normally yieldingly maintained in their upper positions in close proximity to the ring 40 by 20 means of the spring ball latches described. When the respective lugs 53 to 53^e are engaged by suitable cam mechanism to be described the tension of the spring is overcome and the lugs and blocks are adapted to be 25 projected downwardly into the position shown in dotted lines in Fig. 6.

Referring now to Fig. 2, a block or support 54 is suitably secured and rigidly mounted on the top portion or table 2 of 30 the machine. The support has removably secured thereto as by screws 55, a stationary cam member 56 which projects directly under the rotating ring 40 in such manner as to engage the lugs 53 to 53^e and move the 35 same and their blocks 46 to their normal upper position against the ring when the latter revolves, and where the blocks are yieldably maintained by the spring ball latches described.

40. As best seen in Figs. 3 and 10, the support 54 is further provided with a curved stationary cam member 57 so positioned as to project in the path of the long needle butts 58 of the usual needles 3^a, which 45 latter are thereby deflected downwardly and temporarily out of operating position until after they have passed the various cams, carried by the support 54. It will be here understood that the needles having the long butt jacks which are controlled by the stationary cam 57 are the usual needles carried by the needle cylinder for knitting the body of the stocking, and that after being deflected downwardly 50 by said cam, are thereafter projected upwardly to receive thread from the respective main yarn guide fingers hereinabove described, by the usual stationary cam ring (not shown) which is a standard and well known feature of this class of machine. The cam 57 is an added feature of the present improvements and does not act to control the knitting of the needles contacting therewith. Its function is merely to temporarily move these long butted needles

downwardly as an aid to the proper automatic selection of the high splice or design knitting needles as will be described.

The high splice or design needles carried by the needle cylinder, are of preference 70 provided with short length butt jacks which do not extend outwardly as far as the stationary cam 57 (Fig. 13), and consequently these latter needles are not affected by the operation of this cam, but are carried past 75 as the needle cylinder rotates. Mounted for horizontal adjustment or reciprocation on the support 54 and normally retracted from the path of the needles, is a short needle butt jack cam 59, which is slidably supported by 80 means of the screws or projections 60 extending through the elongated aperture 61 in said cam member. This mounting permits the cam to be shifted when desired into the path of the high splice on design needle butt 85 jacks 62 which as before stated are of short length so that the same will clear the stationary cam 57. The automatic mechanism whereby the slideable short needle butt jack 90 cam 59 is projected into the path of the high splice or design needles at the desired and predetermined time, consists of a bell crank lever 63 suitably pivoted at 64 to a bracket 65 secured to the frame of the machine, said bell crank lever having one arm 95 pivoted as at 66 to the outer end of the slideable cam 59. The other arm of the bell crank is pivotally secured at 67 to the upper end of a rod or link 68 guided for vertical reciprocation within a bracket 69 secured to the frame of the machine. The lower end of the rod 68 has a suitable cam or abutment 70 adapted to be engaged by a lug or projection 71 carried on the face of a wheel 72 secured on the end of a shaft 73. The latter is adapted to be intermittently rotated at predetermined intervals from the power source of the machine and will be further described in connection with the operation 100 of the mechanism. It will be stated in this connection that when the lug 71 strikes the lower end of the rod 68 when the wheel is rotated, and in a counter clockwise direction (Fig. 2), the bell crank lever 63 will be rocked on its pivot 64 to project the normally inoperative cam 59 into the path of the short butt jacks of the high splice or design needles, as will be readily apparent. The inner position of the cam 59 after the bell crank 63 has been rocked on its pivot 110 is illustrated in dotted lines in Fig. 10.

A second slideably adjustable cam member 74 is mounted on the block support 54 by means of screws or projections 75 extending through the elongated aperture 76. The adjustable cam member 74 is preferably inclined to the vertical in the opposite direction from the stationary cam member 56, and is further preferably provided with a notched inclined cam face 74^a normally pro-

jecting in the path of all of the heretofore described projecting lugs 53 to 53° of varying length of the blocks 46 carried by the rotating ring 40. The arrangement is such that during the usual knitting of the stocking within the ring member 40 and until the location of the desired stepped high splice is reached, cam 59 is retracted out of the path of the short butt design needles and cam 74 is in the path of all of the lugs 53 to 53°. Therefore, during the usual knitting of the stocking proper, the lugs 53 to 53° are released from their spring ball latches 50 and projected downwardly by the normally inwardly disposed cam 74 as the lugs pass the latter, but the normal operation of the needles is not affected for the reason that the cam 59 is in its normal retracted position out of the path of the short butt high splice or design needles. After being projected to their downward position by the cam member 74, the lugs 53 to 53° are immediately engaged and elevated by the stationary cam member 56 to be yieldingly held by their spring latches 50 until they again arrive at the cam member 74 on the succeeding revolution of the needle cylinder. The slideable cam member 74 is adapted to be intermittently and periodically moved by degrees out of the path of the lugs 53 to 53° at the desired and predetermined time by means of a bell crank lever 77 pivotally mounted at 78 on a suitable bracket secured to the machine frame. One arm of the bell crank projects through a properly disposed aperture 79 in the cam member 74, and the other arm of said bell crank is pivotally secured to the upper end of a rod or link 80. The latter is pivotally secured as at 81 at its lower end to the outer end of a lever 82 pivoted at 83 to a bracket on the machine frame. The inner end of the pivoted lever 82 is or may be offset as illustrated and is provided with a projection or roller 84 adapted to be engaged by the cam surface 85 of an eccentric cam 86 also secured on the end of the intermittently rotating shaft 73. A tension spring 87, attached at one end to the lever 82 and secured at its other end to the frame of the machine, tends to maintain the roller 84 of the lever in engagement with the eccentrically curved cam surface of the cam 86. From the foregoing it will be seen that as the shaft 73 is rotated intermittently and with a stop motion, the roller 84 travels along the curved cam surface of the eccentric cam 86, being maintained in engagement therewith by the spring 87, and gradually the radial distance of the roller from the axis of the shaft is decreased. This results in the lever 82 being rocked on its pivot, the rod 80 moves downwardly, thereby rocking the bell crank 77 on its pivot and moving the slideable cam member 74 outwardly and by degrees successively out of the path of the rotating lugs 53 to 53°. It will be further apparent that by the movement described, the cam 74 will first clear the shortest lugs 53, thereby permitting the operation of the short butt design needles controlled thereby to knit the first step of the high splice design. The cam 74 next clears the next shortest lugs 53° permitting additional design needles to remain in operation, which with the first mentioned design needles, knit the second step of the design, and which because of its increased width (Fig. 11) necessitates the employment of more needles. The outward movement of the cam 74 is continued by steps through the intermittent rotation of the shaft 73, with the result that the additional design needles respectively controlled by each successive pair of lugs of increasing length, are successively brought into operation to knit in a downward direction the succeeding steps of the high splice design, in a manner that will be readily understood. The operation of the above described mechanism to knit the high splice design of stepped configuration at the proper time, and the manner and order in which the various cams and elements described are brought into play to control the needles and effect the design, is as follows:

Shaft 73 is rotated by suitable clutch mechanism (not shown) when the point for commencing the design is reached, the stocking contained within the ring 40 being supported by the needle cylinder and knitted in the usual manner down to this point. The rotation of the shaft 73 in the direction of the arrow (Fig. 2), through the elements described, projects cam 59 into the position shown in dotted lines in Fig. 10, and into the path of the short butt design needles, which heretofore have been clearing this cam and also the stationary cam 57, which latter is only operating to deflect the long butt jack needles as before described. Cam 59 raises butt jacks 62 of the short design needles, or needles at the center of the back of the stocking and extending laterally for the greatest width of the stepped design, to high or up position, thereby placing them in operative relation to catch yarn from the high splicer finger 16, if further mechanism were not employed. The butt jacks 62 controlling the short needles in the center of the back of the stocking and extending for the maximum width of the design, project radially outwardly to be engaged by the cam 59 when the attachment is brought into operation to commence the knitting of the high splice design. The center line of the design to be knitted on the heel of the stocking is indicated by the line A—A in Fig. 2, or just after the ring, which is rotating in a clockwise direction in this figure, has passed the several stationary and adjustable cams 56,

57, 59 and 74 carried by the table 2 of the machine. At substantially the time that the short needle butt jacks 62 for working the 5 design are raised by the cam 59 to be subsequently lowered by lugs 53 to 53° to a mid-point preparatory to working the design, the somewhat longer butt jacks 58 of the remaining needles of the ring, which are not utilized in working the design, strike the 10 cam 57 and are lowered thereby to inoperative position. The stationary cam 57 does not extend inwardly a sufficient distance to be in the path of the short butt jacks of the design needles. The rotating needle cylinder 15 3 and ring 40 next pass cam 74 which at the start of the high splice operation, is in its innermost position toward the ring, as illustrated in Fig. 2, thereby moving all projections or lugs 53 to 53° on the ring down, and 20 the eccentric cam 86 on shaft 73 is in the position shown in said figure. The lugs 53 to 53° after being moved down by cam 74 contact with the short needle butts 62 raised as described by cam 59, and move all of these 25 butts and their corresponding needles downwardly a short distance but out of operative relation to the high splicer finger 16. Immediately thereafter the lugs 53 to 53° strike stationary cam 56 and are again raised to 30 their upper position to be yieldably maintained by their spring latches 50 until they again arrive at the cam 74.

As described above the stocking is being knitted in the usual way down to the point 35 where it is desired to commence the high splice design at the heel, and when the stocking is being knitted the ring element 40 is freely rotating with the needle cylinder 3. The needle butt jacks are performing in 40 their usual manner for the reason that the cam 59 is being held out of operating position as illustrated in Fig. 2 until the shaft 73 is rotated. The lugs 53 to 53° are being 45 released from their spring latches and moved downwardly by the cam 74 and immediately thereafter are moved upwardly by the cam 56 and again maintained in their upper position by their spring latches until the next rotation of the ring. This periodic downward and upward movement of the lugs 53 to 53° does not cause any actuation of the 50 needles until the cam 59 has been moved inwardly.

To bring the mechanism into play for 55 knitting the stepped design, a suitable clutch (not shown) is thrown in to rotate shaft 73 slowly and with a stop motion under power from the machine and in a counterclockwise direction as illustrated by the arrow in Fig. 60 2. As will be seen from this figure the projection 71 carried by the wheel 72 strikes the contact member 70 carried by the lower end of the vertical rod 68 thereby moving the horizontal arm of the bell crank lever 63 upward and this rocking movement of the 65 bell crank lever on its pivot moves the butt-jack cam 59 inwardly into the path of the short butt jack as above described, the remaining and long needle butt jacks continuing to be projected downwardly to lowermost and inoperative position by the cam 57. When this operation is effected to commence the selective movement of the short butt design working needles, it will be seen that the eccentric cam 86 carried by the shaft 73, is also substantially in the position illustrated in Fig. 2. As described above, all of the lugs 53 to 53° are being knocked downwardly by the cam 74 to be subsequently projected upwardly into their normal upper position by the cam 56. These lugs now strike the short or design needle butt jacks 62 which have been lifted from their downward position by the cam 59, and move these needles downwardly to a point where they will not catch thread from the high splice finger 16. No design will be worked as long as all of the lugs 53 to 53° are projected downwardly by the cam 74. However, the intermittent rotation of the shaft 73 is continued, after it has moved cam 59 into the path of the short design needle butts 62, for approximately one-fifth of a complete revolution, where it is caused to come to a stop 80 temporarily by a suitable Geneva or other stop mechanism (not shown).

By this time the roller 84 on the inner end of the pivoted lever 82 has traveled a corresponding distance along the eccentrically curved face 85 of the cam 86. Therefore 100 at the time the shaft is temporarily stopped, this latter cam action results in the lever 82 being rocked a short distance on its pivot 83 by the tension of the spring 87, the latter tending to maintain the roller 84 105 in contact with the eccentric cam surface. The rod or link 80 is therefore moved downwardly, rocking the bell crank lever 77 outwardly on its pivot resulting in the sizable cam 74 being moved outwardly a short 110 distance away from the rotating ring 40. This outward movement of approximately one-sixteenth of an inch is sufficient for the inner and shortest pair of lugs 53 to clear the cam 74. All other pairs of lugs 53° 115 to 53° are still in the path of the cam 74 and continue to be moved downwardly to contact with the remaining butt jacks of the design needles and move the latter downwardly to inoperative position. It will 120 be seen that the butt jacks of the design needles which are controlled by the inner and shortest pair of lugs therefore remain in the operative position to which they have been elevated by the cam 59, and these needles, which may be four or five in number, catch the design thread from the high splice finger 16 to knit the same into the stocking together with the usual thread from the main 125 yarn guide. The timing arrangement is 130

such that the ring 40 makes several revolutions, for instance four or five, while the shaft 73 is stationary, and as this latter shaft turns approximately one-fifth of a revolution at a time, the ratio of revolutions between the ring 40 and the shaft 73 is approximately 25 to 1.

The selected number of revolutions of the ring 40 while the shaft 73 is stationary is sufficient for the needles controlled by the inner pair of lugs 53 to complete the uppermost and central portion of the high splice and which is indicated at 31 in Fig. 11. Thereafter the shaft 73 is caused to rotate for approximately another fifth of a revolution where it again comes to rest. The curvature of the cam 86, through the roller 84 and links and levers described, causes the cam 74 to be moved again outwardly another sixteenth of an inch or a sufficient distance to clear the next shortest pair of lugs 53^a and the needles controlled thereby remain in operation to catch the splicing thread and knit the next step of the design indicated at 32 in Fig. 11. The needles controlled by the innermost pair of lugs 53 remain in operation as will be understood, with the result that a wider design is knitted by the needles controlled by the two innermost pairs of lugs, giving the desired stepped effect. The operation is continued as described to bring other sets of design needles into operation at each one-fifth revolution of the shaft 73, and until all of the lugs 53 to 53^a are cleared by the cam 74, and all of the design needles are operating to knit the design at its lower portion 35 which is of greatest width. At this point the design is completed and the next succeeding partial revolution of the shaft 73 by reason of the curvature indicated at 88 of the cam 86 throws the cam 74 again into the path of all of the lugs 53 to 53^a, thereby rendering all design needles inoperative in the manner hereinabove described. The cam 59 is retracted from the short length butt jacks 62 of the design needles when the design is completed, and the machine completes the stocking in the usual manner and exactly as if the attachment described were not present on the machine.

Referring to Fig. 13, the long needle butts 58, which are not concerned with knitting the high splice, are illustrated as being acted upon by the stationary cam 57 to be moved downwardly temporarily to inoperative position as an aid to properly selecting the short needles for the design operation. In this figure the short needle butt jacks 62, which are not long enough to be acted upon by the stationary cam 57, are shown being moved upwardly to operating position by means of the movable cam 59, which latter is moved inwardly as described when it is

desired to commence the design operation. The stationary cam 56 and movable cam 74 illustrated in Fig. 13 will be understood to have no operative relation to either the long needle butts 58 or the short needle butts 62. These latter stated cams are designed to act only upon the lugs 53 to 53^a of the sliding blocks 46 carried by the rotating ring member 40, and which blocks in turn control the selection of the short needle butts 62 to knit the successive steps of the design.

Figs. 14 and 15 are side views of certain of the mechanism illustrated in Fig. 13; Fig. 14 shows all of the long needle butts 58 being moved downwardly to temporarily inoperative position by the stationary cam 57, and Fig. 15 shows the movable cam 59 operating to move upwardly into position to be engaged by the sliding blocks 46, the short needle butt jacks 62. In their lowermost position when depressed by the cam 57 the needles having the long jacks 58 are unable to take yarn from the high splice yarn finger 16. As heretofore stated the short needle butts 62 are only elevated by the movable cam 59 when it is desired to knit the high splice of the stocking.

Fig. 16 illustrates the action of the movable cam 74 on the lugs 53 to 53^a to move the latter and the blocks 46 carried thereby downwardly to contact with and move to inoperative position the short needle butt jacks 62 which have just been moved upwardly to operative position by cam 59 as illustrated in Fig. 15. The perspective of the lugs 53 to 53^a has been distorted in Fig. 16 to more clearly illustrate the varying lengths of said lugs. These various lengths are most clearly shown in plan view in Fig. 5. Referring further to Fig. 16, as the cam 74 is progressively moved outwardly by the mechanism heretofore described, said cam is cleared by more of the lugs 53 to 53^a, thereby permitting the latter to remain in their uppermost position, and the short needle butts 62 controlled thereby consequently remain in operative position with the result that the stepped design is knitted down to and including the lowermost step which is of greatest width and which is controlled by all of the short butt needles extending between and controlled by all of the lugs 53 to 53^a. It will be observed further in this connection that when the movable cam 74 is in its innermost position all of the lugs 53 to 53^a will be knocked downwardly thereby with the result that the only short butt needles to remain in operative position after being elevated by cam 59, will be the needles between the innermost pair of blocks 46 having the shortest lugs 53. It will be therefore apparent that the first and narrowest step of the design is knitted notwithstanding the fact that all of the lugs 53 to

53° and the blocks 46 carried thereby have been knocked downwardly to move to inoperative position all of the needles controlled by said blocks. This result is most 5 clearly apparent from an inspection of Figs. 17 and 18 in which it will be seen that the narrowest and uppermost step of the design is knitted by the short butt needles 62 between the innermost pair of blocks 46, 10 and these needles therefore remain up in knitting position after being elevated by movable cam 59.

Referring further to Figs 17 and 18 it will be apparent how the downward movement of the blocks 46 moves all of the previously elevated short needle butts 62 to inoperative position. Conversely it will be apparent that as the blocks 46 carrying the lugs 53 to 53° are permitted to remain in 20 uppermost position by the outward movement of cam 74, and commencing from the center of said blocks as shown in these figures, results in the successive steps of the design being knitted until the sixth, 25 uppermost and final step is formed.

What I claim is:—

1. A high splice attachment for spring needle knitting machines, comprising in combination with a rotating needle cylinder, main yarn fingers and a high splicing yarn finger: a ring member concentric with and rotating with the needle cylinder and adapted to control the needles to position a variable number of the needles to knit in a reinforcing yarn.

2. A high splice attachment for spring needle knitting machines, comprising in combination with a rotating needle cylinder, main yarn fingers and a high splicing yarn finger: high splice needles carried by said needle cylinder, a ring member rotating with said needle cylinder, reciprocating blocks carried by said rotating ring for controlling said high splice needles of said cylinder, and cam controlled means for actuating said controlling blocks to bring the latter into engagement with said high splice needles to knit a high splice of predetermined configuration.

3. A high splice attachment for spring needle knitting machines, comprising in combination with a rotating needle cylinder, main yarn fingers and a high splicing yarn finger: a removable ring member rotating with the needle cylinder and adapted to control up to approximately one-half the needles to position a variable number of the needles to knit in a reinforcing yarn.

4. A high splice attachment for spring needle knitting machines, comprising in combination with a rotating needle cylinder, main yarn fingers and a high splicing yarn finger; high splice needles carried by said needle cylinder, a ring member rotating with said needle cylinder, a plurality of yield-

ingly maintained block members, carried by said rotating ring member for controlling said high splice needles, a slidable automatically controlled cam member for progressively actuating said block members to 70 bring the latter into engagement with said high splice needles to knit a high splice of stepped configuration, and means for automatically controlling said actuating means.

5. A high splice attachment for spring 75 needle knitting machines, comprising in combination with a rotating needle cylinder, main yarn guides and a high splicing yarn guide: high splice needles carried by said needle cylinder, a removable ring member 80 concentric with and rotating with said needle cylinder, means carried by said ring member for controlling said high splice needles, means for actuating said controlling means to bring the latter into engagement with 85 said high splice needles to knit a high splice design of predetermined configuration, and means for returning said controlling means to normal position after said controlling means have been engaged by said actuating 90 means.

6. A high splice attachment for spring needle knitting machines, comprising in combination with a rotating needle cylinder, main yarn guides and a high splicing yarn 95 guide: high splice needles carried by said needle cylinder, a removable ring member rotating with said needle cylinder, a plurality of spring controlled block members carried by said ring member for controlling 100 said high splice needles, an automatically controlled cam member for actuating said block members to bring the latter into engagement with said high splice needles to knit a stepped high splice design, and means for returning said block members to normal 105 position after said block members have been engaged by said automatically controlled cam member.

7. A high splice attachment for spring 110 needle knitting machines, comprising in combination with a rotating needle cylinder, main yarn guides and a high splicing yarn guide: high splice needles carried by said needle cylinder, a ring member rotating with 115 said needle cylinder, means carried by said ring member for controlling said high splice needles, means for actuating said controlling means to bring the latter into engagement with up to approximately one-half of said 120 high splice needles to knit a high splice design of predetermined configuration, means for returning said controlling means to normal position after said controlling means have been engaged by said actuating means, and means for automatically controlling said actuating means.

8. A high splice attachment for spring 125 needle knitting machines, comprising in combination with a rotating needle cylinder,

main yarn guides and a high splicing yarn guide: high splice needles carried by said needle cylinder, a ring member rotating with said needle cylinder, a plurality of block members having projecting lugs of various lengths carried by said ring member for controlling said high splice needle butt jacks, said block members being yieldingly maintained in inoperative position, an adjustable cam member for actuating said block members to bring the latter into engagement with said high splice needle butt jacks to knit a high splice design of predetermined and stepped configuration, a stationary cam member for returning said block members to normal inoperative position after said block members have been engaged by said adjustable cam member, and cam controlled mechanism for automatically controlling said adjustable cam member, whereby said high splice needle butt jacks are progressively maintained in operative position to knit said stepped high splice design.

9. A high splice attachment for spring needle knitting machines, comprising in combination with a rotating needle cylinder, main yarn fingers, and a high splicing yarn finger: high splice needles carried by said needle cylinder, a ring member concentric with and rotating with said needle cylinder, means for moving said high splice needles into operative position relative to said high splice finger, and means cooperating with said ring member for controlling up to approximately one-half of said high splice needles after the latter have been moved into operative position, whereby a high splice design of predetermined configuration is knitted by said controlled high splice needles.

10. A high splice attachment for spring needle knitting machines, comprising in combination with a rotating needle cylinder, main yarn fingers and a high splicing yarn finger: high splice needles carried by said needle cylinder, a ring member rotating with said needle cylinder, a normally inoperative adjustable cam member adapted to move said high splice needles into operative position relative to said high splice finger, and cam actuated means cooperating with said ring member for controlling said high splice needles after the latter have been moved into operative position by said normally inoperative adjustable cam member, whereby a high splice design of stepped configuration is knitted by said high splice needles.

11. A high splice attachment for spring needle knitting machines, comprising in combination with a rotating needle cylinder, main yarn fingers and a high splicing yarn finger: means rotating with said needle cylinder, means for moving said high splice needles into operative position relative to said high splicing yarn finger, means carried

by said rotating means for controlling said high splice needles after the latter have been moved into operative position, and means for actuating said controlling means to bring said controlling means into selective engagement with said high splice needles, whereby a high splice design of predetermined configuration is knitted by said high splice needles.

12. A high splice attachment for spring needle knitting machines, comprising in combination with a needle cylinder, main yarn fingers and a high splicing yarn finger: high splice needles carried by said needle cylinder, a ring member carried by said needle cylinder, a normally retracted adjustable cam member adapted to move said high splice needle into operative position relative to said high splicing yarn finger, a plurality of normally retracted block members carried by said ring member for controlling said high splice needles after the latter have been moved into operative position by said adjustable cam member, and a progressively moving cam member for selectively actuating said block members to bring the latter into selective and progressive engagement with said high splice needles, whereby a high splice design of stepped configuration is knitted by said high splice needles.

13. A high splice attachment for spring needle knitting machines, comprising in combination with a rotating needle cylinder, main yarn guides and a high splicing yarn guide: high splice needles carried by said needle cylinder, means attached to and rotating with said needle cylinder, means carried by said rotating means for controlling said high splice needles after said high splice needles have been elevated to operative position, normally inoperative means for elevating said high splice needles into operative position relative to said high splicing yarn guide, means for actuating said controlling means to cause the same to selectively engage said elevated high splice needles to move the same to inoperative position, said normally inoperative needle elevating means being further operative to elevate to operating position the high splice needles which have been moved to inoperative position by said controlling means, and said actuating means being further operative to selectively and progressively maintain said controlling means out of the path of the high splice needles which have been raised to operative position by said normally inoperative means.

14. A high splice attachment for spring needle knitting machines, comprising in combination with a rotating needle cylinder, main yarn fingers and a high splicing yarn finger: means rotating with said needle cylinder, means for moving said high splice needles into operative position relative to said high splicing yarn finger, means carried

14. A high splice attachment for spring needle knitting machines, comprising in combination with a needle cylinder, main yarn guides and a high splicing yarn guide: high splice needles carried by said needle cylinder, a detachable ring member attached to said needle cylinder, spring maintained block members carried by said ring member for controlling the butt jacks of said high splice needles after the same have been elevated to operative position, a normally inoperative cam member for elevating said high splice needles into operative position relative to said high splicing yarn guide, independent cam controlled means for actuating said block members to cause the same to selectively engage said elevated high splice needle butt jacks to move the same to inoperative position, said normally inoperative needle elevating cam member being further operative to engage said needle butt jacks and elevate to operating position the high splice needles which have been moved to inoperative position by said block members, and said independent cam controlled means being further operative to selectively and progressively maintain said block members out of the path of the high splice needles which have been raised to operative position by said normally inoperative cam member, and intermittently operated means for automatically and progressively actuating said normally inoperative elevating member and said independent cam controlled means, whereby a stepped high splice of progressively increasing width is knitted by said high splice needles as the latter are progressively maintained in elevated and operative position.
15. A high splice attachment for spring needle knitting machines, comprising in combination: a high splicing yarn guide, a needle cylinder, having long butt and short butt needles, a ring member attached to said needle cylinder, sliding blocks having projecting lugs of various lengths carried by said ring member for controlling said short butt needles after the latter have been elevated to operative position relative to said high splicing yarn guide, a stationary cam for engaging said long butt needles to temporarily move the same to inoperative position, normally retracted cam means adapted to move into the path of said short butt needles to elevate the same into operative position relative to said high splicing yarn guide, a progressively movable cam member adapted to selectively engage the lugs of said sliding blocks to cause the same to progressively and selectively engage the butt jacks of said elevated short butt needles to move said needles to inoperative position, said normally retracted cam member being further operative to elevate to operative position the short butt needles which have been moved to inoperative position by the engagement of said sliding blocks with said butt jacks, and said movable cam member being further operative to selectively and progressively maintain said sliding blocks out of the path of the short butt needles which have been raised to operative position by said normally retracted cam, a second stationary cam adapted to engage said lugs and return said sliding blocks to normal position after the same have selectively moved said short butt needles to inoperative position, and intermittently operating cam mechanism for automatically actuating said normally retracted needle-elevating cam and progressively operating said movable cam member, whereby a stepped high splice design of progressively increasing width is knitted by said short butt needles as the

latter are selectively and progressively maintained in elevated and operative position relative to said high splicing yarn guide.

17. A high splice attachment for spring needle knitting machines, comprising in combination with a needle cylinder, main yarn guides and a high splicing yarn guide: high splice needles and long butt needles carried by said needle cylinder, a ring member attached to said needle cylinder, a plurality of lugs of various lengths carried by said ring member for controlling said high splice needles after the latter have been elevated to operative position relative to said high splicing yarn guide, a stationary cam member for engaging said long butt needles to temporarily move the same to inoperative position, a movable cam member adapted to move into the path of said high splice needles to elevate the same into operative position relative to said high splicing yarn guide, a second movable cam member for actuating said variously elongated lugs to cause the same to selectively engage the butt jacks of said elevated high splice needles to move said needles to inoperative position, said first mentioned movable cam member being further operative to elevate to operative position the high splice needles which have been moved to inoperative position by said controlling means, and the second of said movable cam members being further operative to selectively and progressively maintain said lugs out of the path of the high splice needles which have been raised to operative position by said first mentioned movable cam member, means for returning said controlling means to normal position after the same have moved said high splice needles to inoperative position, and means for automatically actuating said first mentioned movable cam member and progressively operating the second of said movable cam members, whereby a stepped high splice of progressively increasing width is knitted by said high splice needles as the latter are selectively and progressively maintained in elevated and operative position relative to said high splicing yarn guide.
18. A high splice attachment for spring needle knitting machines, comprising in combination with a needle cylinder, main yarn guides and a high splicing yarn guide: high splice needles carried by said needle cylinder, means attached to and rotating with said needle cylinder, means carried by said rotating means for controlling said high

splice needles after the latter have been elevated to operative position relative to said high splicing yarn guide, normally inoperative means adapted to move into the path of said high splice needles to elevate the same into operative position relative to said high splicing yarn guide, means for actuating said controlling means to cause the same to selectively engage the butt jacks of said elevated high splice needles to move said needles to inoperative position, means for returning said controlling means to normal position after the same have moved said high splice needles to inoperative position, and means for automatically actuating said normally inoperative elevating means and progressively operating said actuating means, whereby a stepped high splice of progressively increasing width is knitted by said high splice needles as the latter are selectively and progressively maintained in elevated and operative position relative to said high splicing yarn guide.

19. An attachment for spring needle knitting machines comprising a ring member adapted to be detachably connected with and concentric to the needle cylinder, and means carried by said ring member adapted to be selectively and progressively actuated to control the high splice needles of said knitting machine, whereby a high splice design of stepped formation is knitted by said high splice needles.

20. An attachment for spring needle knitting machines comprising a ring member adapted to be detachably connected with the needle cylinder, and a plurality of butt engaging lugs of various lengths carried by said ring member and adapted to be selectively and progressively engaged by cam mechanism to automatically control the high splice needles of said knitting machine, whereby a high splice design of stepped formation is knitted by said high splice needles.

21. An attachment for spring needle knitting machines comprising a ring member adapted to be detachably connected to and concentrically surrounding the needle cylinder, means carried by said ring member adapted to be selectively and progressively actuated to control the high splice needles of said knitting machine, and means automatically and progressively engaging said means carried by the ring member, whereby a high splice design of stepped formation is knitted by said high splice needles.

ARTHUR J. MANKIN.
